UNITED STATES PATENT OFFICE.

HERBERT GUETTLER, OF CHICAGO, ILLINOIS, ASSIGNOR TO AMERICAN BARKING DRUM COMPANY, A CORPORATION OF ILLINOIS.

BARKING-DRUM.

1,311,226.

Specification of Letters Patent. Patented July 29, 1919.

Application filed August 26, 1918. Serial No. 251,357.

To all whom it may concern:

Be it known that I, HERBERT GUETTLER, a subject of the King of Norway, residing at Chicago, in the county of Cook, State of Illinois, have invented certain new and useful Improvements in Barking-Drums; and I do hereby declare the following to be a full, clear, and exact description of the invention, such as will enable others skilled in the art to which it appertains to make and use the same.

The present invention relates to bark removing machines of the type wherein the blocks of wood, from which the bark is to be removed, are tumbled in a rotating drum. The improvements comprising the invention reside in the provision, within the drum, of devices for effecting the required tumbling action constructed in such a way as to completely avoid brooming or similar injury, which is liable to occur when tumbling devices of the usual character are employed.

According to the invention, as preferably carried into practice, the drum is made up of rolled steel bars, which extend from end to end thereof and are formed with continuous longitudinal corrugations. The latter occupy the central portions only of the bars, and project inwardly toward the axis of the drum; and they are disposed sufficiently far apart from one another, due to their formation as just described, to provide an interrupted or pocketed, instead of a practically smooth, interior surface within the drum. Consequently, when the drum is in motion and the tumbling of the wood takes place, no injury to the wood will be occasioned, because of the fact that the ends of the blocks will strike against the rounded corrugations, instead of against the sharp edges of the ordinary tumbling devices. The pieces of bark detached in this way from the blocks are discharged from the interior of the drum through longitudinal slots which are produced by spacing the edges of adjacent bars.

An embodiment of the invention is illustrated in the accompanying drawing, where-

50 in—

Figure 1 is a side elevation of a barking drum equipped with the present improvements; Fig. 2 is a transverse section thereof; and Fig. 3 is an enlarged, fragmental per-

spective view of some of the corrugated bars.

Referring more particularly to said drawing, the improved drum, generally designated 5, is preferably cylindrical in shape, as shown, and is made up of skeleton metal bars 7 which extend from end to end thereof and are connected together by a plurality of metal hoops 6 arranged at suitable intervals apart. These bars are constructed of rolled steel, and are provided with longitudinal corrugations 13, which constitute the tumbling devices proper, said corrugations being co-extensive in length with the bars and occupying solely the central portions thereof, so that they are spaced from the marginal edges of the bars. The corrugations project inwardly toward the longitudinal axis of the drum, and are of rounded or U-section; and they are disposed an appreciable distance apart from one another, due to their central arrangement on the bars as above explained, in order to provide an interrupted, instead of a practically smooth, interior surface, thereby insuring the positive tumbling of the blocks. The bars themselves have their mutually-adjacent longitudinal or marginal edges spaced far enough apart to form slots 8, through which the detached pieces of bark may be discharged into the tank or the like (not shown) wherein the drum is mounted. The interruptions above referred to are in the nature of longitudinal pockets which are sufficiently wide to enable them to catch the corners of the blocks therein during the rotation of the drum, whereby the blocks are positively forced to travel part way around with the drum. The slots 8 extend centrally along the bottoms of the pockets.

The drum is supported by means of devices which alternate with the hoops 6 and are here shown as comprising pairs of angle iron hoops 9 arranged with their flights projecting outwardly from the drum and disposed opposite and in close proximity to each other to receive between them solid rings 10, the latter and the flights of the hoops being riveted together, while the bases of the hoops are secured in like manner to the corrugated bars 7. The rings 10 may rest upon or otherwise engage rollers or other supports of any desired character, illustration of this feature being omitted

as not involved in the actual invention. Rotation of the drum may likewise be effected in any approved manner; for instance, by providing at the center of the 5 drum a sprocket ring 11 which encircles said drum and is designed for engagement with driving gearing (not shown) which, in turn, is driven from a suitable source of power, the said sprocket ring being mounted 10 between the out-turned flights of a pair of angle iron hoops 12.

The devices for tumbling the blocks of wood comprise the afore-mentioned, inwardly-directed corrugations 13, which are 15 separated far enough apart to insure their effecting the necessary tumbling action, as above explained, as distinguished from a mere sliding movement of the blocks; but instead of the ends of the blocks striking 20 against the tumbling devices (which are usually in the form of angle bars having their flights directed inwardly of the drum) and being split or broomed by the sharp edges thereof, they will hit only the rounded 25 surfaces of the corrugations, and will, in consequence, be uninjured.

Further description of the invention, its mode of operation, and its advantages, is deemed unnecessary in view of the foregoing, and is, accordingly, omitted; but it may 30 be stated that while the preferred embodiment of the invention is disclosed herein, no limitation to the precise structural details of such disclosure is intended, since modifications and changes with relation to the improved tumbling devices may well be made 35 within the scope of the invention as claimed, and the said devices may obviously be used in other and different types of drums.

40 I claim as my invention:

1. In a barking apparatus, a hollow, rotatable container for the blocks having a plurality of tumbling devices each consisting entirely of a bar of substantially U-section, the rounded bases of said bars being directed inwardly toward the center of said container.

2. In a barking apparatus, a hollow, rotatable drum having a plurality of one-piece tumbling devices each consisting of a bar of substantially U-section having its rounded base directed inwardly toward the center of the drum, said devices being spaced an appreciable distance apart from one another so as to form pockets between them adapted to catch the corners of the blocks therein during the rotation of the drum and thereby positively force said blocks to travel part way around with said drum.

60 3. In a barking apparatus, a hollow, rotatable drum comprising a plurality of skel-

eton bars of substantially U-section extending from end to end thereof in parallel relation, and having their rounded bases directed inwardly toward the axis of the 65 drum, said bars being spaced an appreciable distance apart from one another to form pockets between them adapted to catch the corners of the blocks therein during the rotation of the drum and thereby positively 70 force said blocks to travel part way around with said drum.

4. In a barking apparatus, a hollow, rotatable container for the blocks, comprising a plurality of bars having longitudinal corrugations which are directed inwardly toward the center of the container.

5. A barking drum comprising a plurality of longitudinally corrugated bars which extend from end to end thereof in parallel 75 relation, the corrugations of said bars being directed inwardly toward the axis of the drum.

6. A barking drum comprising a plurality of longitudinally corrugated bars which extend from end to end thereof in parallel relation, the corrugations of said bars occupying solely the central portions thereof and being directed inwardly toward the axis of the drum, so as to provide an interrupted 85 tumbling surface within the drum.

7. A barking drum comprising a plurality of bars formed with continuous longitudinal corrugations which are spaced from the marginal edges of the bars and are directed inwardly 95 toward the axis of the drum so as to provide an interrupted tumbling surface within the drum, the said edges of adjacent bars being spaced apart to provide longitudinal 100 slots for the discharge of detached pieces of bark therethrough.

8. A barking drum comprising a plurality of bars formed with continuous longitudinal projections of substantially U-section which are spaced from the marginal edges 105 of the bars and are directed inwardly toward the axis of the drum so as to provide an interrupted tumbling surface within the drum.

9. A barking drum comprising a plurality of bars formed with continuous longitudinal projections of substantially U-section which are spaced from the marginal edges of the bars and are directed inwardly toward the axis of the drum so as to provide an interrupted 110 tumbling surface within the drum, the said edges of adjacent bars being spaced apart to provide longitudinal slots for the discharge of detached pieces of bark therethrough.

In testimony whereof I affix my signature.
HERBERT GUETTLER.
